UNITED STATES PATENT OFFICE.

JOHN H. DALE, OF NEW YORK, N. Y., ASSIGNOR TO DALE LIGHTING FIXTURE CO., INC.,
A CORPORATION OF NEW YORK.

INCANDESCENT LAMP.

1,204,653.

Specification of Letters Patent.

Patented Nov. 14, 1916.

Application filed January 20, 1915. Serial No. 3,197.

To all whom it may concern:

Be it known that I, JOHN H. DALE, a citizen of the United States, residing at the city of New York, in the borough of Manhattan and State of New York, have invented certain new and useful Improvements in Incandescent Lamps, of which the following is a full, clear, and exact description.

This invention relates to electric incandescent lamps and resides in the provision of a ventilated lamp bulb.

In the more recent types of lamps of high candle power, and especially in nitrogen filled lamps, after the lamp has remained lighted for a short period of time the intense heat of the filament is transmitted to the gas in the bulb, the bulb itself, and also to the attached shell and socket plug, so that all of these parts soon reach a relatively high temperature, the result of which is a rapid deterioration of the filament, due to the heat of the nitrogen gas which surrounds it, and hence a shortening of the life of the lamp. The intense heating of the socket plug and shell is also objectionable, since it will, by conduction, cause the heating of the socket to which it is connected, and will also cause a breaking down of the insulation of the lead wires to the socket, resulting in a short circuit, or else the heated socket, may come in contact with some inflammable material, and in each instance the danger of fire is imminent.

It is, therefore, the purpose of my invention to provide means for cooling the bulb, the gas contained therein and the socket plug and shell, and accordingly my invention contemplates the provision of a ventilating air conduit arranged in the interior of the sealed bulb through which a constant current of air circulates which is preferably conducted to the interior of the shell and socket where it is permitted to escape through ventilating openings in the shell or socket. These air conduits are preferably arranged for a portion of their length adjacent the lamp filament, and in that way a variation in the temperature of the air is set up within the conduit, which will cause the air to flow toward the shell and socket plug.

In addition to this, my invention contemplates auxiliary ducts, which, without interfering with the sealed condition of the bulb, pass from the exterior of the lamp bulb

through a portion thereof above the filament and communicate with the main air conduit to provide an excess of cool air which will be carried into the interior of the shell and socket plug to reduce to a material extent 60 the temperature of the same.

The air passages or conduits may be arranged in any convenient manner in the lamp bulb, and a plurality of them may be provided if desired.

In the accompanying drawings several embodiments of the invention are shown, which are to be construed in a descriptive and not in a limiting sense, as other equally convenient arrangements of the air duct may 70 be provided, and yet come within the purview of the invention.

In Figure 1 of the drawings there is shown the usual form of a nitrogen filled lamp equipped with a ventilating passage in accordance with the principle of my invention. Figs. 2, 3 and 4 show modifications of the arrangement of the ventilating air conduit.

The structure of the incandescent lamp 80 shown in each of the figures of the drawings is similar to that which is at present employed in nitrogen filled lamps, to which my invention is especially adapted. The bulb of the lamp, which is sealed, comprises a 85 spherical body portion 1, to which is joined a substantially cylindrical neck 2. Projecting downwardly from the upper end of the neck is a glass stem 3 carrying at its lower end a depending glass pedestal 4. Downwardly directed radiating metallic arms 5 are attached to the pedestal and diverge at their lower ends, being arranged in somewhat semiconical shape. These arms carry at their lower ends a filament 6. The leads 90 for connecting the filament to a source of current are designated 7 and 8, respectively, and pass downwardly through the glass stem 3 in the usual manner. Attached to the upper end of the neck by a layer of 100 cement is a cylindrical shell 9. This shell carries the ordinary socket plug 10, which is joined thereto by a layer of cement 11, in the usual manner. One of the leads 7 is soldered to the shell, as at 12, and the other one, 105 8, is connected with the insulated center contact 13 of the socket plug.

As stated, when a lamp of this character is lighted and current is passing through the filament the bulb, nitrogen gas and 110

socket plug become heated to high temperature. This phenomenon is not so apparent in the ordinary vacuum incandescent lamp, and it is probable that the excess of heat 5 present is due to the greater convection and radiation of the heat from the filament when nitrogen is used in the lamp bulb. Some of the heat, however, is conducted by the glass bulb to the shell and socket plug. In order 10 to cool the parts of the lamp a main ventilating air conduit 14 is provided. As shown in Fig. 1 this conduit consists of a glass tube which, at its lower end, is sealed and forms a portion of the bulb, and then extends upwardly in the interior of the bulb until it reaches a point substantially on a level with the filament, where it is curved in a horizontal plane around the filament, and then extends upwardly along the wall of the 15 neck and, at its upper end is again sealed to the glass bulb. In the construction of the lamp the conduit 14 may be blown integral with the lamp bulb, as shown, or it may be formed from a separate tube, in which instance it would be placed in position and sealed before the air was exhausted from the bulb and the same filled with the nitrogen through the tip 16. The air which circulates freely in the hollow shell and socket 20 plug is permitted to escape from the interior of the shell and socket plug through the spaced vent holes 17 in the periphery of the shell. In order to maintain the plug and shell at a still lower temperature an auxiliary duct or opening 18 may be provided, which connects the main duct 14 to the atmosphere at a point above the filament. 25

When a lamp of the character described remains lighted for a considerable period of time the heat generated by the filament will be transmitted by convection and radiation to the portion of the column of air within the conduit 14 which surrounds the filament. The air within the hollow shell and socket 30 plug will also become heated to a greater extent than the atmospheric air which surrounds the bulb. The variations of temperature of the air within the conduit will therefore cause a current of air to flow 35 through the same toward the neck of the bulb and to circulate freely within the hollow shell and socket plug, escaping through the vent openings or holes 17. This air, while it is necessarily heated to some extent 40 in its passage through the conduit 14, nevertheless materially reduces the temperature of the gas within the bulb, and hence the bulb itself, as well as the shell and socket plug, and in this manner the life of the lamp 45 is increased, since the filament will not deteriorate as rapidly as where the gas within the bulb is permitted to reach a much higher temperature. The reduction of the temperature 50 of the shell and socket plug is also sufficient to render the likelihood of fire remote. 55

It may also be desirable to utilize the auxiliary duct 18, in which instance the current of air which passes through the main duct 14 will suck in a volume of the colder atmospheric air surrounding the neck of the bulb, which will pass into the interior of the hollow shell and socket plug as before, and will thereby cause a greater reduction of 60 temperature in these parts.

The form of lamp shown in Fig. 2 may 65 also be utilized, but in this instance the standard form of incandescent lamp must be somewhat changed. The stem 3 of the lamp is hollow and, instead of being sealed at its lower end, is extended by means of a tube 21 through the spherical portion of the bulb to the periphery of the same, where it is sealed. The stem is provided at its free end with an annular shoulder 23 which forms a support for the radiating arm 5 carrying the filament 6. The other structural features of the lamp are similar to the one already described, and in its operation, the air will be caused to flow through the conduit provided into the interior of the 80 shell and socket plug and out through the 85 openings therein, as before.

In Fig. 3 a lamp is shown in which a pair of conduits 24 and 25 are provided, which extend from the periphery of the 90 lamp adjacent its tip 16, through the spherical portion and neck of the lamp, leading into the chamber formed by the hollow shell and socket plug, which, as before, is provided with vent openings 17. Auxiliary 95 air ducts 26 may be provided in each of these conduits. When the lamp is lighted the air flows through these conduits in the manner previously described, and since a plurality of them are provided the gas in the bulb, 100 the bulb, and the shell and socket, will obviously be cooled to a lower temperature, due to the greater volume of air which passes through the conduits.

In Fig. 4 an arrangement of conduits is 110 shown which is designed to cool only the gas within the bulb and the bulb itself, and in this instance the air conduits which are designated 27 and 28 pass through only the spherical portion of the lamp bulb, and 115 will, since a current of air will circulate in the same, cause a material reduction in the temperature of the gas within the bulb.

The invention is equally applicable to 120 various other forms of incandescent lamp bulbs in which a different arrangement of an air conduit may be feasible, and as I deem the formation of a sealed lamp bulb with a ventilating passage therein to be novel to me such forms and arrangements 125 are intended to come within the purview of this invention as particularly pointed out in the appended claims.

The ventilating tubes may be of any desired cross section, the particular contour 130

of the cross section being determined by the character and uses to which the lamp is to be put and it is intended that the term tubular as used in the claims, is sufficiently broad to cover a tube of a regular or irregular shape in cross section.

5 I claim—

1. The combination, with an incandescent lamp comprising a lamp bulb having a body portion, a neck and a socket plug attached to said neck, of a tubular member passing through the body and neck of said bulb and opening into a space between the socket plug and neck of the bulb.
- 10 2. The combination, with an incandescent lamp comprising a bulb consisting of a body portion and a neck, a filament in said body portion and a hollow socket plug attached to said neck, of a tubular member passing through said body portion and neck of said bulb and leading into a chamber formed between the hollow socket plug and neck, and means for permitting the escape of air from said chamber.
- 15 3. The combination, with an incandescent lamp comprising a lamp bulb consisting of a body portion and neck, a filament in said body portion and a hollow shell and socket plug attached to said neck, of a tubular member passing through the body of said lamp through the neck of the bulb and leading into the hollow chamber formed between the hollow shell and socket plug and neck of said bulb, said shell having vent
- 20 openings therein.
- 25 4. The combination, with an incandescent lamp comprising a lamp bulb consisting of a body portion and neck, a filament in said body portion and a hollow shell and socket plug attached to said neck, of a tubular

member passing through the body of said lamp and having a portion thereof adjacent said filament, the remainder of said tubular member passing through the neck of the bulb and leading into the hollow chamber formed between the hollow shell and socket plug and neck of said bulb, said shell having vent openings therein.

5. The combination, with an incandescent lamp comprising a lamp bulb having a body portion and containing a filament, a neck and a socket plug attached to said neck, of a ventilating air conduit passing through the body and neck of said bulb and opening into a space between the socket plug and neck, and an auxiliary conduit leading from the atmosphere into said main conduit at a point above said filament.

6. The combination, with an incandescent lamp comprising a sealed lamp bulb and a hollow base attached thereto, of a ventilating air conduit passing through said bulb and leading into the interior of said base, said base having vent openings therein.

7. The combination, with an incandescent lamp comprising a sealed lamp bulb containing a light yielding element and a hollow base attached thereto, of an air ventilating conduit passing through said bulb and leading into the interior of said hollow base, and an auxiliary conduit leading from said atmosphere into said main conduit at a point above said light yielding element, and said base having vent openings therein.

In witness whereof, I subscribe my signature, in the presence of two witnesses.

JOHN H. DALE.
